SELENIUM BOILER

Cleveland Scudder Smith, Jr., West Orange, N. J., and Sol Blumenthal, Indianapolis, Ind.; said Smith assignor to Samuel Ruben, New Rochelle, N. Y., and said Blumenthal assignor to P. R. Mallory & Co., Inc., Indianapolis, Ind., a corporation of Delaware

Application September 5, 1945, Serial No. 614,518

6 Claims. (Cl. 263--36)

1
This invention relates to a vaporizer in which the material to be vaporized is introduced at the top and the vapors are discharged from the bottom, and more particularly to a selenium boiler or vaporizer for depositing selenium on a base plate in the manufacture of selenium rectifiers.

An object of the invention is to provide a vaporizer of the above type having novel and improved details of construction and features of operation.

Another object is to provide a vaporizer into which the selenium may be continuously introduced and which discharges the vapors in a downward direction for deposition onto a base plate which is passed thereunder.

Various other objects and advantages will be apparent as the nature of the invention is more fully disclosed.

Although the novel features which are believed to be characteristic of this invention are pointed out more particularly in the claims appended hereto, the invention itself may be better understood by referring to the following description, taken in connection with the accompanying drawing in which a specific embodiment thereof has been set forth for purposes of illustration.

In the drawing:

Fig. 1 is a transverse vertical section through a vaporizer embodying the present invention;

Fig. 2 is a longitudinal vertical section on a reduced scale, taken on the line 2--2 of Fig. 1; and

Fig. 3 is a broken horizontal section taken on the line 3--3 of Fig. 2.

Referring to the drawing more in detail, the invention is shown as comprising a boiler having a pair of side walls 10, end walls 11, and a bottom wall 12 provided with a transverse slit 3 through which the vapors are emitted and extending substantially across the bottom of the vaporizer.

A transverse plate 15 positioned somewhat below the top closes the upper part of the vaporizer and provides an open chamber 16 for the reception of the material to be vaporized, such as selenium shot. A plurality of vertically spaced horizontal trays 20 to 25 extend between the end walls 11 in the vaporizer. These trays are of less width than the interior of the vaporizer between the side walls 10 staggered, alternate trays being attached to alternate side walls. The trays are provided with flanges 30 to 35 respectively which are secured to the inside surfaces of the walls 10 by suitable means as by welding. The trays are also provided with flanges 40 to 45 which serve to retain the liquid in each tray to a predetermined level. The flanges 40 to 45 are

2
provided with openings 50 to 54 respectively through which the liquid from each tray overflows on to the next succeeding tray. The flanges 50 to 54 are provided with downwardly extending lips 60 to 64 respectively having surfaces over which the overflow liquid drains and positioned to direct the liquid onto the tray below. A heating means is provided for each tray. In the form shown, the heating means comprises tubes 70 to 75 disposed beneath the respective trays and contains heating rods 80 to 85 respectively which may comprise electric resistance rods or other suitable heating elements. These tubes 70 to 75 are so positioned that they are shielded by the downwardly extending lips 60 to 64 from contact with the liquid which overflows the respective trays. A pair of tubes 75 and heating elements 85 are shown as disposed on opposite sides of the slit 3 at the bottom of the vaporizer.

30 The molten selenium flows from the plate 15 to the first tray 20 through a vapor lock comprising a plurality of bells 90 which extend through openings in the plate 15 and are provided with slits 91 above said plate to receive the molten **25** selenium, and at their bottom are provided with openings 92 below the level of the liquid on the tray 20.

35 In the operation of this device the solid or liquid selenium is supplied to the chamber 16 and is melted by the heat developed by the boiler. The molten selenium then flows through the slits 91 and onto the tray 20 where a portion thereof is vaporized by the heat produced by the rod 80. The remaining liquid then overflows through the openings 50 in the flange 40 and drips down onto the next succeeding tray 21 wherein a further portion of the liquid is vaporized by the heat developed by the heating element 81, and so on, until the liquid reaches some tray such as tray **40** 23 or 24 from which the remaining liquid selenium is vaporized. The conditions are maintained so that the liquid is entirely vaporized or before reaching tray 25 so that only vapor is present in the lower part of the boiler. This may be accomplished by suitable regulation of the temperatures and the rate of introduction of the selenium into the boiler.

45 The vapor passes downwardly through the slit 13 onto the exposed surface such as the surface of a base plate 100 which is disposed beneath the boiler. By moving the base plate 100 across the path of the vapors issuing from the slit 13 a deposit 101 of selenium is obtained thereon.

50 The boiler may be made from Vycor or quartz glass and may be fabricated from standard flat

4
formed in the bottom of said chamber to discharge the vapors therefrom.

5 4. A vaporizer comprising a closed chamber, a plurality of horizontal trays disposed in vertically spaced relationship in said chamber, a top closure for said chamber having means to receive the material for vaporization thereon, means including a vapor lock supplying molten material through said closure means onto the topmost tray, said 10 trays being staggered and disposed adjacent of the side walls of said chamber, a downwardly extending overflow lip on the free edge of each tray positioned to direct overflow liquid onto the tray below, a heating member disposed beneath each of said trays for heating and vaporizing the liquid thereon, and a vapor slit formed in the bottom of said chamber to discharge the vapors therefrom.

15 5. The method of vaporizing selenium which comprises introducing the selenium in solid state into a heating zone, melting the selenium in said zone, passing the liquid selenium downwardly through a vaporizing zone, maintaining conditions of flow and heat in said zone suited to vaporize the entire liquid content before reaching the bottom of said zone, and discharging the vapors downwardly from the bottom of said zone.

20 6. The method of vaporizing selenium which comprises introducing the selenium in solid state into a heating zone, melting the selenium in said zone, passing the liquid selenium downwardly through a vaporizing zone in a plurality of stages, maintaining conditions of flow and heat in said zone suited to vaporize the entire liquid content before reaching the bottom of said zone, and discharging the vapors downwardly from the bottom of said zone.
